CLAIM

The ornamental design for a carrying case for an archer's bow or the like, substantially as shown and described.

DESCRIPTION

FIG. 1 is a front elevational view of a carrying case for an archer's bow or the like showing our new design, the opposite side being a mirror image thereof;

FIG. 2 is a top plan view thereof;

FIG. 3 is a bottom plan view thereof; and

FIG. 4 is a left end elevational view.

Fig. 1.

Fig. 2.

Fig. 3.

Fig. 4.
